UNITED STATES PATENT OFFICE.

MARTIN ALTOLAGUIRRE AND JOAQUIN ZUBILLAGA, OF VEDADO, CUBA.

PROCESS OF PRODUCING SUGAR.

No. 910,037.

Specification of Letters Patent.

Patented Jan. 19, 1909.

Application filed September 30, 1907. Serial No. 395,153.

To all whom it may concern:

Be it known that we, MARTIN ALTOLAGUIRRE and JOAQUIN ZUBILLAGA, citizens of the United States, residing at Vedado, Cuba, have invented new and useful Improvements in Processes of Producing Sugar, of which the following is a specification.

Our invention pertains to the production of sugar; and it consists in the process, hereinafter described and claimed, for converting low grade sugars into first sugars of high test, 96° polariscope test or higher, and without loss of the crystallizable sugar on low grades, this with a view of rendering it expedient to produce high test sugar only in a sugar house instead of the usual two kinds.

The invention will be fully understood from the following description and claims when the same are read in connection with the drawings, accompanying and forming part of this specification, in which: The figure is a view, partly in elevation and partly in vertical section, of one apparatus which may be employed to advantage in the practice of our process.

Referring by letter to the said drawing: A is so much of a vacuum pan as is necessary to illustrate our invention; it being definitely understood that the said vacuum pan may be of the conventional construction or of any other construction compatible with our invention, without involving departure from the scope of the same as claimed.

B is a suitably supported receptacle, and C is a suitable pump having its induction orifice connected through a valved pipe D with the bottom of the receptacle B, and its ejection orifice connected through a valved pipe E with the vacuum pan A.

Journalized in suitable bearings at the top of the receptacle B is a horizontal shaft F carrying fast and loose pulleys a b and a worm gear c, and journalized in suitable bearings at the bottom and top of the receptacle is a vertical shaft G on which is fixed a gear wheel H, intermeshed with the worm gear c, whereby it will be apparent that on rotation of the shaft F, the shaft G will be rotated about its axis. At intervals of its height, the shaft G is provided with radially extending blades I, fixed to turn with the shaft. The alternate blades I are disposed at right angles to each other, and between each pair of blades is arranged a fixed cross-bar J. These cross-bars J are alternately

arranged at right angles to each other, and each is preferably made up of sections connected at their outer ends to the vertical wall of the receptacle B and at their inner ends to collar sections which are loosely secured on the shaft G.

By virtue of the described arrangement of the blades I, relative to the bars J, it will be understood that when the receptacle B is charged with sugar and syrup as presently described and the shaft G is in motion, the moving blades I in coöperation with the fixed bars J will expeditiously and thoroughly work the sugar and syrup together in a homogeneous mass.

In carrying out our novel process we charge the receptacle B with, say forty bags, of dry, low grade sugar of about 86° polariscope test. We then add to the sugar charge a little sugar syrup or solution of sugar containing about 45% of water, such, for instance, as the ordinary syrup of sugar houses—i. e., the liquid coming from the concentration of juice; the quantity of said syrup ranging between 4.5% to 10% on the weight of the said forty bags of dry, low-grade sugar. After the receptacle B is supplied with the dry sugar and syrup, the shaft G is set in motion to thoroughly mix the said ingredients, and then the pump C is started and the mixture is pumped from the receptacle B to the vacuum pan A. With this done, the vacuum pan will be about half full and grained with the ordinary syrup. If it be now assumed that at the time of supplying the mass of sugar and syrup to the vacuum pan as stated the pan contained a mass grained in the pan from the syrup, it will be manifest that we mix in the pan two masses both of which are grained. At this point new additions of the syrup are made to the vacuum pan, when the small crystals of both of the masses therein will commence to grow and will continue growing in size or volume until the capacity of the vacuum pan is reached. We then drop out the contents of the vacuum pan and the said contents or mass is centrifugated with the result that one class of sugar is obtained and that of high test.

We employ high-density syrup only in the process because such syrup does not dissolve the grain and serves as a medium to introduce the prepared mass into the pan. We also employ such syrup for the reason that it would be difficult to introduce dry sugar

into the pan, but if the same was feasible it would never mix well in the pan but would remain in lumps.

It will be gathered from the foregoing that for every 100 lbs. of sugar of 86° polariscope test, we recuperate after the operation the 86 lbs. of pure sugar changed into larger crystals because from the start to the finish of the operation we do not dissolve the original individual small crystals and hence we get back the sugar without loss on the weight of the test of sugar.

There are three ways in which the mass described can be supplied to the vacuum pan, viz: First. Introducing in the vacuum pan about three-fourths of the volume of the pan of the mass and finishing the strike with syrup. Second. Crystallizing the contents of the pan with syrup, and when the grain 20 is well formed in the pan the contents are concentrated a little and the mass prepared as stated is at this moment introduced into the pan, and the strike is finished with ordinary syrup. Third. When the contents of 25 the pan are dropped out, leaving in the pan about one-third of its contents already grained, the prepared mass is introduced over the said contents, and the strike is finished with syrup. The vacuum pan need 30 not stop during the introduction of the prepared mass.

The syrup used in the practice of our process should not be confounded with molasses, and with this understanding it will be appreciated that our process is designed to and as a matter of fact produces high grade sugar only; the sugar used in the practice of the process coming from molasses after the same have been cooked to a point of super 35 saturation, cooled and purged in centrifugals or other suitable means.

It will be noted from the foregoing that the pump does not take the mass from the receptacle B by suction. On the other hand 45 the mass gravitates to the cylinder of the pump, which is constructed with a view of adapting it to pump semisolid masses, and the pump has but to push or force the mass, received in its cylinder, to the vacuum pan A.

50 We prefer to employ the receptacle described and the appurtenances thereof for mixing the sugar and syrup, but we do not desire to be understood as confining ourselves to the same, inasmuch as any approved

apparatus may be employed for said purpose, nor do we desire to be understood as confining ourselves to the pump for transferring the mass from the receptacle to the vacuum pan, since such transfer may be accomplished in any suitable manner without involving departure from the scope of our invention as defined in the following claims.

Having described our invention, what we claim and desire to secure by Letters-Patent, is:

1. The process described of converting low-grade sugars into sugars of high test, which consists in introducing into a vacuum pan a mixture of dry low-grade sugar and solution of sugar containing approximately 45% 70 of water, and adding a similar solution of sugar containing approximately 45% of water to the pan, whereby the sugar of the last named solution is precipitated on the crystals of the low-grade sugar, and the grain of 75 sugar is conserved.

2. The process described of converting low-grade sugars into sugars of high test, which consists in introducing into a vacuum pan, over a mass of grained contents therein, a 80 mixture of dry low-grade sugar and solution of sugar containing approximately 45% of water, and adding a similar solution of sugar containing approximately 45% of water to the pan, whereby the sugar of the last 85 named solution is precipitated on the crystals of the low-grade sugar, and the grain of sugar is conserved.

3. The process described of converting low-grade sugars into sugars of high test, which 90 consists in introducing into a vacuum pan, over a mass of grained and concentrated contents therein, a mixture of dry low-grade sugar and solution of sugar containing approximately 45% of water, and adding a 95 similar solution of sugar containing approximately 45% of water to the pan, whereby the sugar of the last named solution is precipitated on the crystals of the low-grade sugar, and the grain of sugar is conserved. 100

In testimony whereof we have hereunto set our hands in presence of two subscribing witnesses.

MARTIN ALTOLAGUIRRE.
JOAQUIN ZUBILLAGA.
